United States Patent Office

Des. 227,115
Patented June 5, 1973

227,115

COMPUTER TERMINAL

Robert J. Abbott, Jr., Toledo, Ohio, assignor to
Owens-Illinois, Inc.

Filed July 24, 1972, Ser. No. 274,701

Term of patent 14 years

Int. Cl. D14—02

U.S. Cl. D26—5 C

Fig. 1

Fig. 3

Fig. 4

Fig. 2

FIG. 1

FIG. 1 is a front perspective view of a computer terminal embodying my new design;

FIG. 2 is a top plan view thereof;

FIG. 3 is a left side elevational view thereof, the right side being a mirror image of the side shown;

FIG. 4 is a rear elevational view thereof; and

FIG. 5 is a bottom plan view thereof.

I claim:

The ornamental design for a computer terminal, as shown and described.
